LOCK

Henry G. Voight, New Haven, Conn., assignor to
 Sargent & Company, New Haven, Conn., a corporation of Connecticut

Application January 27, 1941, Serial No. 376,019

3 Claims. (Cl. 292—169)

This invention relates to door locks or latches, and more particularly to a lock for the front door of a building, although it will be understood that it may be employed in any location in which is desired a lock having the novel characteristics embodied in the present structure.

Moreover, the invention relates also to a so-called tubular lock, or a lock having a cylindrical casing which may be inserted through a cylindrical opening made in the edge of a door, and is in many respects similar to the lock shown in my application Serial No. 345,109, filed July 12, 1940, the present structure embodying improvements over or additions to the device shown in that application.

In the application above referred to, the lock is provided with a dogging plunger accessible from the face of the door when the latter is closed to dog the latch against operation by the outer knob. This plunger is guided in the walls of the case and is pushed inwardly to dog the outer knob against operation. Detent means are provided to releasably hold the dogging member in operative position until it is manually released, which release is effected by pulling the plunger outwardly by the exposed portion thereof. While such a device operates in a satisfactory manner for the most part, it is found that it is easier to push the plunger inwardly than it is to grasp the exposed end thereof and pull it outwardly.

The present invention is designed to overcome this disadvantage, and to provide a pair of push buttons connected by a walking beam, and also operatively connected to the dogging member so that one of these buttons is pressed inwardly to dog the latch against operation while the other is pressed inwardly to release the dogging means, the movement of one button to its inner position serving through the walking beam to draw the other button to its outer position, and vice versa.

One object of the present invention is the provision of a door lock having improved means for operation of the latch-dogging means, particularly with respect to moving such means to inoperative position.

A still further object of the invention is the provision of a front door lock having a latch or knob-dogging member movable transversely of the movement of the latch and accessible for operation upon one side of the door when the latter is closed, with improved means for withdrawing the dogging member to inoperative position.

A still further object of the invention is the provision of a lock having a knob-dogging member extending outwardly through the face of the

door for operation when the door is closed, with a walking beam structure whereby the dogging means may be moved either to inoperative or operative position by pressure upon a button at the face of the door.

A still further object of the invention is the provision of a lock of the character described having a knob-dogging plunger and a walking beam structure arranged within the knob rose at the inner side of the door to operate said plunger, the walking beam structure comprising a pair of push buttons or like members extending through the rose to be accessible for operation at the inner side of the door when the latter is closed.

To these and other ends the invention consists in the novel features and combinations of parts to be hereinafter described and claimed.

In the accompanying drawing:

Fig. 1 is a front elevational view of a door having my improved lock applied thereto, the knob having been removed for the sake of clearness;

Fig. 2 is a sectional view on line 2—2 of Fig. 1;

Fig. 3 is an interior face view of the inner rose and walking beam structure housed therein;

Fig. 4 is a sectional view on line 4—4 of Fig. 3;

Fig. 5 is a sectional view of the walking beam structure taken on line 5—5 of Fig. 3; and

Fig. 6 is a detail elevational view of the walking beam.

To illustrate a preferred embodiment of my invention, I have shown a portion of a door at 10, upon which is mounted a lock comprising a tubular casing 11 having reciprocably mounted therein a bolt 12 normally urged outwardly by the bolt spring 13, which acts against the bolt head and against a post 14 provided on the walls of the casing. The lock may also be provided with a bolt-controlling plunger 15 of usual form, which serves, as shown in my prior application above referred to and as is well known in the art, to prevent the retraction of the bolt by a tool inserted between the edge of the door and the door jamb.

Rotatably mounted in the walls of the casing are inner and outer hubs 16 and 17 carrying rollbacks 18 and 19, respectively. These rollbacks are operated by inner and outer knob spindles 20 and 21, respectively, upon which are mounted the inner and outer knobs 22 and 23. It will be understood that the spindles 20 and 21 are independently operable by their respective knobs, so that either of the knobs may be rotated independently of the other to rotate the rollback carried thereby and retract the latch 13. As the above-described structure and the connections between

the rollbacks 18 and 19 and the bolt 12 may be identical with the corresponding parts shown in my previous application referred to, it is deemed unnecessary to further illustrate them herein.

Slidably mounted in the opposite walls of the lock case 11 is a plunger 25 carrying a detent 26 adapted to engage in a recess 27 in a laterally extended portion of the rollback 19 operated by the outside knob, so that, when the plunger is pushed inwardly from its position shown in Fig. 2, and the detent engages in the recess 27, the rollback 19 will be dogged against operation. The plunger is releasably retained in its inner and outer positions by means of the engagement of the spring-pressed detent 29 with a projection 30 arranged on the side of the plunger 25 opposite that which carries the detent 26.

A push button 31 is adjustably connected by means of its threaded end 32 with the plunger 25, the button extending outwardly through an opening in the inner rose 33 so as to be accessible for operation at the inside of the door at one side of the shank of the knob 22. This push button is provided with an intermediate reduced portion 34 for a purpose which will be hereinafter described. This push button 31 may be provided with a recess 35 within which extends a finger 36 on the rose 33 to prevent rotation of the button after the rose has been secured upon the door by means of the screws 37 (Fig. 1).

It will be apparent that with the foregoing structure the push button 31 may be pushed inwardly so as to move the plunger 25 inwardly to knob-dogging position. In order that the plunger may also be moved outwardly by pressure upon a button at the inside of the door, a walking beam structure is provided and disposed within the rose 33, as will now be described.

This structure comprises a casing or housing formed of spaced plates 40 and 41, the plate 40 having upper and lower portions 42 and 43 turned laterally and embraced by crimped portions 44 and 45 so as to conveniently and cheaply secure the two plates in spaced relation. These plates are provided with aligned openings 46 and 47 through which passes the knob spindle, and each of these openings has upper and lower extended recesses 48 and 49 into which swivelly projects semi-circular members 50 and 51 secured upon each side of a walking beam 52 at both upper and lower edges thereof, so that the walking beam will be swiveled or pivoted between the two plates for rocking movement about a vertical axis.

The button 31 extends through openings in the plates 40 and 41, and the reduced portion 34 thereof is received in a recess 53 in one end of the walking beam, so that when the latter is moved pivotally the button will be moved longitudinally, and vice versa. The walking beam 52 is provided with a central opening 54 through which the inner knob spindle 20 loosely passes, and upon the end of this member opposite the recess 53 is mounted a second push button 55 which extends outwardly through openings in the plate 41 and rose 33 so as to be accessible for operation at the inside of the door.

The assembled position of the parts of the walking beam structure is shown in Fig. 5, and it will be seen from Fig. 2 that this structure is, when mounted on the door, housed within the rose 33 so as to lie between the outer wall of the rose 33 and the face of the door. In mounting the parts in position, the walking beam structure is applied to the door before the rose is secured thereto, and the button 31 is screwed into the

plunger 25 until the rear plate 40 engages the face of the door. The rose is then applied and secured in position by the screws 37, and if necessary the button 31 may be backed off a short

5 distance so as to cause the groove 35 to register with the tongue 36 in the rose. The walking beam structure will by this means be mounted in position, and the buttons will be substantially concealed by the inner knob, but will be 10 readily accessible for operation. When the button 31 is depressed, the detent 26 will engage the rollback 19 so as to prevent operation of the outside knob. When it is desired to release the dogging member, the button 55 will be depressed, 15 which will throw the opposite end of the member 52 outwardly, and thus draw outwardly the button 31 and the plunger 25 so as to withdraw the detent 26 from the recess 27, thus leaving the bolt free for retraction by the outside 20 knob.

The outer plate 41 may be provided with upwardly and downwardly extending ears 56 on each side of the members 45, which ears are adapted to embrace the inwardly displaced sleeves

25 57 around the openings in the rose which receive the screws 37, so that the walking beam structure will be held against displacement within the rose.

While I have shown and described a preferred 30 embodiment of my invention, it will be understood that it is not to be limited to all of the details shown, but is capable of modification and variation within the spirit of the invention and within the scope of the appended claims.

35 What I claim is:

1. In a door lock, a case, a bolt reciprocably mounted therein, independently rotatable inner and outer knobs, mechanism connecting each of said knobs to said bolt for operation thereof, a 40 dogging member slidably carried by the walls of the case to dog the outer knob against operation, a walking beam structure for operating the dogging means accessible for operation at the inside of the door when the latter is closed, a rose about the inner knob, said walking beam structure being housed within said rose, said structure comprising a pair of plates, a lever pivoted between said plates at a point intermediate its ends, a push button operatively connected to each end of the lever and projecting through said rose, and one of said buttons being directly connected to said dogging member.

2. In a door lock, a case, a bolt reciprocably mounted therein, independently rotatable inner and outer knobs, mechanism connecting each of said knobs to said bolt for operation thereof, a dogging member slidably carried by the walls of the case to dog the outer knob against operation, a walking beam structure for operating the dogging means accessible for operation at the inside of the door when the latter is closed, a rose about the inner knob, said walking beam structure being housed within said rose, said structure comprising a pair of plates, a lever pivoted between said plates at a point intermediate its ends, a push button operatively connected to each end of the lever and projecting through said rose, and one of said buttons being adjustably connected to said dogging member, and means for retaining said button in adjusted position.

3. In a door lock, a case, a bolt reciprocably mounted therein, independently rotatable inner and outer knobs, mechanism connecting each of said knobs to said bolt for operation thereof, a

dogging member slidably carried by the walls of the case to dog the outer knob against operation, a walking beam structure for operating the dogging means accessible for operation at the inside of the door when the latter is closed, a rose about the inner knob, said walking beam structure being housed within said rose, said structure comprising a pair of plates secured together

5 in spaced relation and having cooperating openings therein, a walking beam mounted between said plates and provided with projecting portions rockingly mounted in said openings, and a push button mounted on each end of said beam and projecting through openings in the rose.

HENRY G. VOIGHT.
